(57) **CLAIM**

The ornamental design for a hooded garment, as shown and described.

DESCRIPTION

FIG. 1 is a front perspective of the hooded garment; FIG. 2 is a front view of the hooded garment; FIG. 3 is a back view of the hooded garment; FIG. 4 is a left side view of the hooded garment, the right side being a mirror image to the left side view; and, FIG. 5 is a top view of the hooded garment.

The short dashed broken lines around the bottom edge and opening for the face of the hooded garment depict claimed stitching. The larger dashed broken lines along the interior openings of the hooded garment define the extent of the claimed design and form no part of the claimed design. The shade lines that resemble a quilted pattern defined by broken lines applied to the surfaces of the hooded garment represent a contrast in appearance.
